UNITED STATES PATENT OFFICE.

HERMAN P. PORTER, OF JACKSONVILLE, FLORIDA.

WINDOW-SASH.

1,388,121.

Specification of Letters Patent. Patented Aug. 16, 1921.

Application filed December 1, 1919. Serial No. 341,658.

To all whom it may concern:

Be it known that I, HERMAN P. PORTER, a citizen of the United States, residing at Jacksonville, in the county of Duval and State of Florida, have invented certain new and useful Improvements in Window-Sashes, of which the following is a specification.

This invention relates to certain new and novel improvements in sliding window-sashes to be used in connection with the standard type of window frames, wherein each sliding sash-frame is provided with an inner sash so connected thereto as to be capable of being swung inward and held in open adjusted position for the purpose of ventilation, easily and readily removed therefrom within the room for the purpose of ventilation and cleaning, and so constructed as to prevent the entrance of cold air or moisture to the inside of the window, said invention constituting an improvement on Letters Patent granted to me under date of June 19, 1917, No. 1,280,514.

The main object of this invention is to provide novel, simple, economical, durable and efficient window sashes, so constructed that both the upper and the lower inner sash may be swung inward to any suitable or desirable extent and held in such adjusted position without causing a direct draft, and that when the inner sashes are closed they will effectually prevent the entrance of cold air or moisture to the inside of the window, said inner sashes being removable.

Another object of the invention is to so construct the window sashes that both the upper and lower inner sashes carrying the window pane or panes may be readily removed from the outer sash frames within the room for cleansing, renewal or repair of connections therewith, or the renewal of the glass pane or panes, thereby avoiding all danger to which window cleaners and repairers are usually subjected.

Another object of the invention is to provide sashes having safe, durable, efficient and economical means for locking the sashes together within the window frame when the inner sash is in its open as well as its closed position, and means secured to the sashes and concealed within the same when closed, for adjusting each inner sash inwardly to any suitable extent and securing it in its ad-

justed position to furnish the desired ventilation for the rooms of a building during either its occupancy or vacancy. The link system herein shown from 7 to 22, is shown and described in an application filed by me December 1, 1919, Serial No. 341,659.

Further objects of the invention are to so construct the inner and outer sashes that they will be substantially weatherproof when in closed position; that all tendency to break the window panes, when the inner sash is slammed, forcibly closed, or should for any reason be accidentally and rapidly closed from its open adjusted position, will be avoided; and to provide means connected with both sashes whereby when in closed position they will be practically sealed and safely and securely locked together.

The foregoing and such other objects as may appear from the ensuing description are attained by the novel features of construction, arrangement, combination and location of parts hereinafter more fully described, illustrated in the accompanying drawings, and particularly pointed out in the claims appended hereto, it being understood that slight changes in the form, proportion, and minor details of the construction may be resorted to without departing from the spirit or sacrificing any of the advantages of the invention.

Reference now being had to the accompanying drawings which form a part of this specification and in which similar numerals of reference indicate like parts throughout the several views, it will be seen that:

Figure 1 is a front elevation of the improved window sashes and their connections embodying my invention, removed from the window frame.

Fig. 2 is a longitudinal section of the same, showing by dotted lines the inner sash adjusted to an inward position.

Fig. 3 is an enlarged edge view of the inner sash removed.

Fig. 4 is an enlarged rear elevation of a portion of the inner sash showing the side frames or rails thereof broken away near the bottom.

Fig. 5 is a detail partly in section, showing the means for locking the upper rail or frame of both sashes together.

Fig. 6 is a detail plan of the keeper shown in Fig. 5.

Fig. 7 is a detail partly in section showing the means of pivotally locking the lower portion of the sashes together.

Fig. 8 is a detail plan of the keeper shown 5 in Fig. 7.

Fig. 9 is an enlarged longitudinal section through the frames of both sashes showing the side frame or rails of each inner sash broken away and the lower portion of the 10 outer sash in contact with the window sill.

Fig. 10 is an enlarged elevation of a portion of the inner sash showing the pivoted links for removably connecting the inner and outer sashes together.

Fig. 11 is a detail partly in section of the lower portion of the outer sash showing the position of the keeper secured thereto, and

Fig. 12 is detail in elevation of the outer 20 edge of the lower portion of both the inner and outer sash showing them connected together by the pivoted bolt connection.

In carrying out my invention as illustrated, the numeral 1, designates the lower 25 outer sash frame, and 2 the upper outer sash frame, said sash frames being fitted so as to freely slide in a window frame of the standard well known construction provided with the usual sash weights, cords and pulleys 30 (not shown), such as are ordinarily employed in connection with sliding sashes.

Each of the outer sash frames is provided along the inner edge of its lower rail with a plurality of beveled faces 3, 4 and 5, adapted 35 to contact with the complementary beveled edge of the lower rail of the inner sash, and each inner sash frame is provided along the outer edges of its top and side rails with similar beveled faces 3, 4 and 5 adapted to 40 contact with the complementary beveled inner faces of the top and side rails of the outer sash, said beveled and complementary faces coöperating to produce a smooth and gradual wedging contact, as clearly shown 45 in Figs. 2 and 9. The outer sash frame carries the inner sash frame 6 removably and adjustably connected to it so as to be adapted to swing inwardly and be securely fastened thereto.

To each side rail of both the upper and lower outer sashes is secured a stationary keeper 7, the latter being fixedly connected within a suitable recess, and provided with a plurality of countersunk openings 8 55 adapted to receive the heads of the set screw fastenings 9 so that said heads will rest flush with the outer surface of the keeper. The folding arms or links 10 and 11 are connected with said stationary keepers, the 60 longer arm 10 being permanently secured to the keeper 7, while the perforated end portion of the shorter arm 11 is pivotally and detachably secured to a pin 12, fixedly secured to a keeper 13, which is permanently

secured, in the manner described with reference to keeper 7, to each side rail of the inner sash, said pin 12 being recessed at 14 for the reception of a locking latch 15 pivotally secured to the arm 11. The meeting end of each of the arms 10 and 11 is formed 65 with an embossed connection integral therewith and forming a series of ribs and corrugations 16 formed radially thereon, the meeting ends of said arms being pivotally connected together by a headed rivet 17, so 70 that their ends will interlock with each other thereby locking the swinging inner sash at any desirable adjusted position until it is desired to shut or close the swinging sash, and fixedly secured to the arm 11 by a 75 rivet 18 is one end of a flat plate spring 19, the outer or other end of the spring being resiliently secured beneath the head of the rivet 17, said spring exerting sufficient pressure to cause the corrugations and ribs 80 formed on the meeting ends to interlock with each other when adjusted to register, and at the same time permitting the yielding of the jointed ends sufficiently to allow the desired adjustment of the arms for the 85 purpose, as will be readily understood. Each of the keepers 7 and 13 is provided with a flanged portion 20 extending outward from its base member 21, and the upper end 90 of each of the arms 10 and 11 is provided 95 with a curved or cam-shaped end portion 22 which is adapted to contact with said flanged portion of the keeper before the jointed ends of the arms reach a dead center, thereby avoiding the necessity of breaking the joint at the meeting ends of the arms, since the outer end portion of each arm will come into contact with the flanged portion of its respective keeper, thus constituting a stop to limit the inward movement 100 of the inner sash.

The outer face of the upper end cross bar 23 of each inner sash is provided with a transverse groove 24, which terminates near each side thereof, and communicates with 105 a longitudinal groove 24', formed in the inner rabbet of the outer face in each side rail of each inner sash, said groove 24' terminating at the lower end of the inner sash, and connecting with a groove 25, formed 110 within the inner face of the lower rail of both the upper and lower outer sashes whereby a drainage chamber or outlet is formed at the bottom portion of both the upper and lower sashes for the discharge of 115 all moisture, which may be forced in between the inner and outer sashes, from said chamber to the outer side of the window, said drainage chamber, in connection with the beveled inner faces of the inner and outer sash frames forming a substantially 120 weatherproof window.

Formed within the upper cross rail of

both the upper and lower outer sashes near each end thereof is a recess for the reception of a spring bolt 26 provided with a cone-shaped head 27, and secured to and 65
 5 carried by the upper rail of the inner sash near each end of said upper rail, the upper or flared head portion of said bolt engaging with the recessed edge portion 28, of the keeper 29, when projected against said 70
 10 keeper, thereby taking up the slack and forcing the inner sash into close contact with the outer sash, said keeper 29 being fixedly secured in a suitable recess formed within the inner face of the outer sash top 75
 15 rail.

The lower portion of each side rail of the inner sash is provided with a laterally movable slidable securing bolt 30 adapted to be projected within a recess formed in the inner 80
 20 face of the side rail of each outer sash and to each of said side rails of the outer sash is suitably and fixedly secured a keeper 31 with a horizontally elongated slotted opening 32 which is engaged by the bolt 30, and permits 85
 25 a limited inward swinging movement of the lower portion of the inner sash, said bolt 30 at the same time serving to lock the inner and outer sashes together to prevent any one 90
 30 on the outside from lifting the inner sash from the outer sash, since the bolt can be operated only from the inside, and when the said bolt is moved outward from engagement with its keeper the inner sash may be easily removed for the purpose of cleaning 95
 35 the pane, or for any other purpose desired.

The central portion of the upper sash rail of the lower outer sash is provided with an opening therethrough for the reception of a 100
 40 suitable bolt 33 which is adapted to enter a suitable recess formed in the lower rail of the upper outer sash whereby the meeting rails of the sashes are securely locked together in close contact. The meeting rail 105
 45 sash lock is shown and claimed in Patent No. 1,346,677, granted to me July 13, 1920, on an application filed by me December 2, 1919, Serial No. 341,905.

By reference to Figs. 1, 2 and 5 of the 110
 50 drawings it will be seen that each spring locking bolt 26 carried by the top rail of the inner upper sash is provided with a depending chain having at its lower end a ring 26^x, whereby said locking bolt may be easily extracted and the inner sash swung inward to any suitable extent while the lower end portion of each locking bolt carried by the top rail of the inner lower sash is fitted a ring 27^x, and each of said rings 26^x and 27^x 115
 55 may be readily grasped by the fingers for the proper and easy manipulation of both inner sashes for ventilating purposes, and while a chain is shown secured to the locking bolts 26 of the upper sash it will be understood 120
 60 that an ornamental cord or rope of any desirable type or construction, preferably provided with a ring at its lower end, may be utilized for the purpose stated.

When it is desired to ventilate the rooms of a house during its vacancy, it is simply 70
 necessary to lock the meeting rails of the sashes together by means of the locking bolt 33, then by a downward and inward pressure on the rings suspended from each locking bolt 26 unlock each bolt, and swing its inner 75
 sash inward to any desired extent, thereby providing the desired ventilation during absence from the premises, and since each inner sash is locked to the outer sash near its bottom portion by the locking bolts 30 which 80
 can only be operated from the inside, the entrance of unauthorized persons by means of the windows is thereby absolutely prevented, and when the weather is extremely 85
 warm and it is desired to obtain a full volume of the outside atmosphere within the room it is simply necessary to remove both inner sashes thereby leaving substantially an unobstructed area within the window frame 90
 for the ingress of air without any interference whatever with the ordinary wire gauze screen usually secured to the outer face of the window frame.

When it is desired to remove the inner upper sash for the purpose of cleaning or repairs, the lower sash is elevated to contact with the upper portion of the window frame and the upper sash is lowered into the position shown by dotted lines in Fig. 2, the sashes being so constructed that when they 95
 100 are caused to assume the said position the upper bar or rail of the inner sash carrying the locking bolts is clear of the lower rail of the lower outer sash and the bolts are then extracted; the inner sash is swung inward, and each pivoted locking latch 15 carried by the arm 11 is disengaged from its respective pin 12, and each arm 11 detached from said pin; the locking bolts 30 then being extracted from the outer sash frame, the inner sash becomes entirely released and may be readily removed to a suitable position within the room for the desired purpose, and when it is desired to replace the inner sash the 105
 operation is readily accomplished by placing the lower rail of the inner sash upon the bottom rail of the outer sash, then sliding each of the locking bolts 30 into engagement with the outer sash, then passing the perforation in each of the arms 11 over the respective pins 12 into engagement therewith, and pressing each pivoted locking latch 15 over the outer face of the arm 11 and into engagement with the slotted portion 14 of said pin 12, when the said inner sash may 110
 115 be swung into its closed position into close contact with the outer sash and securely locked thereto by the locking bolts 26 in the 120
 125

manner hereinbefore described. Both the upper and lower inner sashes are removed and replaced in the manner herein referred to.

It will be perceived that the inner edges 5 of the outer sash and the outer edges of the inner sash frames are so beveled and grooved that in case the inner sash is swung inwardly to any degree, and should be caused to be slammed for any reason to its closed position 10 the beveled portions and grooves of the sashes serve to perform a smooth, easy and gradual contacting effect thereby avoiding all tendency of breaking the glass pane or panes carried by the inner sash. Further, 15 the groove forms a small chamber in the outer face of the top rail of the inner sash, and in each side rail, and the groove formed in the inner face of the bottom rail of the outer sash coacts with the curved formation 20 at the lower edge of the inner sash to form an enlarged air and drainage chamber, and since this chamber is in communication with said grooves it serves to collect all the moisture therein, whence it is discharged along 25 the beveled face 5 to the outside of the window.

It will also be seen that the foldable arms connected to a keeper fixedly secured to the side rails of each of the outer and inner 30 sashes, are so constructed and arranged that when the inner sash rests in its closed position the said arms and keepers are concealed within the recesses formed within the side rails of each of the outer and inner sashes, 35 respectively.

Having thus described my invention, what I claim and desire to secure by Letters Patent is:—

1. An outer sash frame, in combination 40 with an inner sash frame removably and adjustably secured to the outer frame, said inner frame having a longitudinal groove formed within the outer face of its top rail terminating within said rail, and a longitudinal groove formed in the outer face of each side rail communicating with the first named longitudinal groove, and a longitudinal groove formed in the inner face of the bottom rail of the outer sash frame communicating with said longitudinal grooves formed in the side rails, whereby a drainage 50 chamber is formed between the inner and outer sash frames.

2. An outer sash frame with its inner 55 edges provided with a plurality of beveled surfaces, in combination with an inner sash frame removably and adjustably secured to the outer frame having a plurality of complementary beveled surfaces formed on its outer edges and adapted to engage the beveled edges of the outer frame, said inner frame having a longitudinal groove formed within the outer face of its top rail terminating within said rail, and communicating 60 with a longitudinal groove formed in

the outer face of each side rail and with a longitudinal groove formed in the inner face of the bottom rail of the outer sash frame to form a drainage chamber between the inner and outer sash frames. 70

3. An outer sash frame formed with a plurality of inner rabbeted edges each having a beveled face, in combination with an inner sash frame removably and adjustably secured to the outer frame having a plurality of complementary beveled faces adapted to engage with the beveled faces on the outer frame, the top rail of the inner sash having a longitudinal groove formed within its outer rabbet, communicating with a longitudinal groove formed within the outer rabbet of each of its side rails, said longitudinal grooves communicating with a longitudinal groove formed in the inner rabbet of the bottom rail of the outer sash frame, thereby forming a drainage chamber between said inner and outer sash frames. 80 85

4. An outer sash frame, in combination with an inner sash frame, said inner sash frame having a longitudinal groove formed within the outer face of its top rail, a longitudinal groove formed within the outer face of each side rail communicating with said transverse groove, and a groove formed within the inner face of the lower rail of the outer frame communicating with said longitudinal grooves, thereby forming a drainage chamber at the lower portion of the sash frame and serving to drain all moisture to the outside of a window. 90 95 100

5. In window construction, the combination with an upper and a lower outer sash frame, of an inner sash removably and adjustably secured to each outer frame, each inner sash provided with a groove formed within the outer face of each top rail, and a longitudinal groove within the outer face of each side rail communicating with a groove formed within the inner face of the bottom rail of each outer frame for forming a drainage chamber between the said inner and outer sash frames. 105 110 115

6. An outer sash frame, in combination with an inner sash frame removably and adjustably secured to the outer frame, the inner edges of the outer sash and the outer edges of the inner sash each being provided with a plurality of beveled faces adapted to contact with each other, a plurality of locking bolts secured to the top rail of the inner sash, the inner headed portion of each bolt engaging with a keeper secured to the outer sash frame, and a laterally movable pivoted slidable locking bolt carried by each side rail of the inner sash near the bottom thereof adapted to limit the inward movement of said inner sash and to lock the sashes together at their bottom portion. 120 125 130

7. In window construction, the combination with an upper and a lower outer sash

both the upper and lower outer sashes near each end thereof is a recess for the reception of a spring bolt 26 provided with a cone-shaped head 27, and secured to and carried by the upper rail of the inner sash near each end of said upper rail, the upper or flared head portion of said bolt engaging with the recessed edge portion 28, of the keeper 29, when projected against said keeper, thereby taking up the slack and forcing the inner sash into close contact with the outer sash, said keeper 29 being fixedly secured in a suitable recess formed within the inner face of the outer sash top rail.

The lower portion of each side rail of the inner sash is provided with a laterally movable slidable securing bolt 30 adapted to be projected within a recess formed in the inner face of the side rail of each outer sash and to each of said side rails of the outer sash is suitably and fixedly secured a keeper 31 with a horizontally elongated slotted opening 32 which is engaged by the bolt 30, and permits a limited inward swinging movement of the lower portion of the inner sash, said bolt 30 at the same time serving to lock the inner and outer sashes together to prevent any one on the outside from lifting the inner sash from the outer sash, since the bolt can be operated only from the inside, and when the said bolt is moved outward from engagement with its keeper the inner sash may be easily removed for the purpose of cleaning the pane, or for any other purpose desired.

The central portion of the upper sash rail of the lower outer sash is provided with an opening therethrough for the reception of a suitable bolt 33 which is adapted to enter a suitable recess formed in the lower rail of the upper outer sash whereby the meeting rails of the sashes are securely locked together in close contact. The meeting rail sash lock is shown and claimed in Patent No. 1,346,677, granted to me July 13, 1920, on an application filed by me December 2, 1919, Serial No. 341,905.

By reference to Figs. 1, 2 and 5 of the drawings it will be seen that each spring locking bolt 26 carried by the top rail of the inner upper sash is provided with a depending chain having at its lower end a ring 26^x, whereby said locking bolt may be easily extracted and the inner sash swung inward to any suitable extent while the lower end portion of each locking bolt carried by the top rail of the inner lower sash is fitted a ring 27^x, and each of said rings 26^x, and 27^x may be readily grasped by the fingers for the proper and easy manipulation of both inner sashes for ventilating purposes, and while a chain is shown secured to the locking bolts 26 of the upper sash it will be understood

that an ornamental cord or rope of any desirable type or construction, preferably provided with a ring at its lower end, may be utilized for the purpose stated.

When it is desired to ventilate the rooms of a house during its vacancy, it is simply necessary to lock the meeting rails of the sashes together by means of the locking bolt 33, then by a downward and inward pressure on the rings suspended from each locking bolt 26 unlock each bolt, and swing its inner sash inward to any desired extent, thereby providing the desired ventilation during absence from the premises, and since each inner sash is locked to the outer sash near its bottom portion by the locking bolts 30 which can only be operated from the inside, the entrance of unauthorized persons by means of the windows is thereby absolutely prevented, and when the weather is extremely warm and it is desired to obtain a full volume of the outside atmosphere within the room it is simply necessary to remove both inner sashes thereby leaving substantially an unobstructed area within the window frame for the ingress of air without any interference whatever with the ordinary wire gauze screen usually secured to the outer face of the window frame.

When it is desired to remove the inner upper sash for the purpose of cleaning or repairs, the lower sash is elevated to contact with the upper portion of the window frame and the upper sash is lowered into the position shown by dotted lines in Fig. 2, the sashes being so constructed that when they are caused to assume the said position the upper bar or rail of the inner sash carrying the locking bolts is clear of the lower rail of the lower outer sash and the bolts are then extracted; the inner sash is swung inward, and each pivoted locking latch 15 carried by the arm 11 is disengaged from its respective pin 12, and each arm 11 detached from said pin; the locking bolts 30 then being extracted from the outer sash frame, the inner sash becomes entirely released and may be readily removed to a suitable position within the room for the desired purpose, and when it is desired to replace the inner sash the operation is readily accomplished by placing the lower rail of the inner sash upon the bottom rail of the outer sash, then sliding each of the locking bolts 30 into engagement with the outer sash, then passing the perforation in each of the arms 11 over the respective pins 12 into engagement therewith, and pressing each pivoted locking latch 15 over the outer face of the arm 11 and into engagement with the slotted portion 14 of said pin 12, when the said inner sash may be swung into its closed position into close contact with the outer sash and securely locked thereto by the locking bolts 26 in the

95

100

105

110

115

120

125

manner hereinbefore described. Both the upper and lower inner sashes are removed and replaced in the manner herein referred to.

It will be perceived that the inner edges 5 of the outer sash and the outer edges of the inner sash frames are so beveled and grooved that in case the inner sash is swung inwardly to any degree, and should be caused to be slammed for any reason to its closed position 10 the beveled portions and grooves of the sashes serve to perform a smooth, easy and gradual contacting effect thereby avoiding all tendency of breaking the glass pane or panes carried by the inner sash. Further, 15 the groove forms a small chamber in the outer face of the top rail of the inner sash, and in each side rail, and the groove formed in the inner face of the bottom rail of the outer sash coacts with the curved formation 20 at the lower edge of the inner sash to form an enlarged air and drainage chamber, and since this chamber is in communication with said grooves it serves to collect all the moisture therein, whence it is discharged along 25 the beveled face 5 to the outside of the window.

It will also be seen that the foldable arms connected to a keeper fixedly secured to the side rails of each of the outer and inner 30 sashes, are so constructed and arranged that when the inner sash rests in its closed position the said arms and keepers are concealed within the recesses formed within the side rails of each of the outer and inner sashes, 35 respectively.

Having thus described my invention, what I claim and desire to secure by Letters Patent is:-

1. An outer sash frame, in combination 40 with an inner sash frame removably and adjustably secured to the outer frame, said inner frame having a longitudinal groove formed within the outer face of its top rail terminating within said rail, and a longitudinal groove formed in the outer face of each side rail communicating with the first named longitudinal groove, and a longitudinal groove formed in the inner face of the bottom rail of the outer sash frame communicating with said longitudinal grooves formed in the side rails, whereby a drainage chamber is formed between the inner and outer sash frames.

2. An outer sash frame with its inner 55 edges provided with a plurality of beveled surfaces, in combination with an inner sash frame removably and adjustably secured to the outer frame having a plurality of complementary beveled surfaces formed on its outer edges and adapted to engage the beveled edges of the outer frame, said inner frame having a longitudinal groove formed within the outer face of its top rail terminating within said rail, and communicating 60 with a longitudinal groove formed in

the outer face of each side rail and with a longitudinal groove formed in the inner face of the bottom rail of the outer sash frame to form a drainage chamber between the inner and outer sash frames.

3. An outer sash frame formed with a plurality of inner rabbeted edges each having a beveled face, in combination with an inner sash frame removably and adjustably secured to the outer frame having a plurality of complementary beveled faces adapted to engage with the beveled faces on the outer frame, the top rail of the inner sash having a longitudinal groove formed within its outer rabbet, communicating with a longitudinal groove formed within the outer rabbet of each of its side rails, said longitudinal grooves communicating with a longitudinal groove formed in the inner rabbet of the bottom rail of the outer sash frame, thereby forming a drainage chamber between said inner and outer sash frames.

4. An outer sash frame, in combination with an inner sash frame, said inner sash frame having a longitudinal groove formed within the outer face of its top rail, a longitudinal groove formed within the outer face of each side rail communicating with said transverse groove, and a groove formed within the inner face of the lower rail of the outer frame communicating with said longitudinal grooves, thereby forming a drainage chamber at the lower portion of the sash frame and serving to drain all moisture to the outside of a window.

5. In window construction, the combination with an upper and a lower outer sash frame, of an inner sash removably and adjustably secured to each outer frame, each inner sash provided with a groove formed within the outer face of each top rail, and a longitudinal groove within the outer face of each side rail communicating with a groove formed within the inner face of the bottom rail of each outer frame for forming a drainage chamber between the said inner and outer sash frames.

6. An outer sash frame, in combination with an inner sash frame removably and adjustably secured to the outer frame, the inner edges of the outer sash and the outer edges of the inner sash each being provided with a plurality of beveled faces adapted to contact with each other, a plurality of locking bolts secured to the top rail of the inner sash, the inner headed portion of each bolt engaging with a keeper secured to the outer sash frame, and a laterally movable pivoted slideable locking bolt carried by each side rail of the inner sash near the bottom thereof adapted to limit the inward movement of said inner sash and to lock the sashes together at their bottom portion.

7. In window construction, the combination with an upper and a lower outer sash

- frame, of an inner sash removably and adjustably secured to each outer frame, a plurality of locking bolts secured to the top rail of the inner sash, each bolt having a cone-shaped headed portion adapted to engage with the recessed edge of a keeper secured to the outer sash frame to take up the slack between the meeting edges of said frames and force a close contact therebetween, a horizontally elongated slotted keeper secured to the inner face of the outer sash, and a laterally movable pivoted slidable locking bolt secured to each side rail of the inner sash adapted to adjustably engage said keeper to limit the inward movement of the inner sash and at the same time lock the sashes together at their bottom portion.
8. In window construction, the combination with an upper and a lower outer sash frame, of an inner sash removably and adjustably secured to each outer frame, a plurality of laterally movable pivoted slideable bolts carried at the lower portion of each inner sash, each bolt being adapted to engage a horizontally elongated slotted keeper secured to the inner face of the outer sash frame for limiting the inward movement of the inner sash and locking the sashes together near the bottom, and a plurality of locking bolts, each of said bolts having a cone-shaped headed portion and being secured to the top rail of each inner sash, the end portion of each last named bolt being adapted to be forced into contact with the central recessed edge of a keeper, said keeper being secured to the top rail of the outer sash frame, whereby the slack between the meeting edges of the sash frames is taken up thus permitting a close wedging contact of the frames at their upper ends.
9. In window construction, the combination with an upper and a lower outer sash frame, the inner frame being removably and adjustably secured to said outer frame, said inner frame having its outer edges formed with a plurality of beveled faces adapted to engage with complementary beveled faces formed on the inner faces of the outer frame, the outer edges of the top and side rails of the inner frame having formed therein communicating drainage grooves, a plurality of locking bolts secured to the upper rail of the inner sash frame for securely locking the upper portion of the sashes together, and a plurality of pivoted slideable locking bolts secured to the bottom portion of the inner sash frame for locking the bottom portions of the frames together.
10. An outer sash frame, in combination with an inner sash frame removably and adjustably fitted in said outer frame and adapted to swing inward on said frame, longitudinal communicating drainage chambers formed between the meeting faces of the inner and outer sash frames, a jointed link connection for yieldingly limiting the inward movement of the removable sash and for securely locking the sash frames in contact, means for permitting the sash frames to be disengaged, and means carried by said jointed link to retain the removable sash in its adjusted inward position.
11. In window construction, the combination with an outer and an inner sash frame, the inner frame being removably and adjustably secured to said outer frame, and adapted to swing inward on said frame, longitudinal communicating drainage chambers formed between the meeting faces of the inner and outer sash frames, jointed links connected for yieldingly limiting the inward movement of the removable sash, means for securing the jointed links to each frame, means for securely locking the jointed links to the frames, means for permitting the sash frames to be disengaged and means carried by said links to retain the removable sash in its adjusted inward positions.
12. In window construction, the combination with an upper and a lower outer sash frame, of an inner sash removably and adjustably secured to each outer frame and adapted to swing inward on said frame, a jointed link connection for yieldingly limiting the inward movement of the inner sash, means permanently secured to each frame for securing each link connection thereto, means for locking the jointed links to said frames, means for releasably securing the inner sash to the outer one, means carried by said link connection to retain the inner sash in its adjusted inward position, and means formed by each link connection and adapted to contact with the means permanently secured to each frame to limit the inward movement of said removable sash.
13. In window construction, the combination with an upper and a lower outer sash frame, of an inner sash removably and adjustably secured to each outer frame, a jointed link connection for yieldingly limiting the inward movement of the inner sash, a plurality of locking bolts carried by the upper rail of each inner sash, a plurality of slideable pivot bolts carried by the lower portion of said inner sash, the inner edge of the outer frame and the outer edge of the inner sash frame being provided with a plurality of beveled faces and adapted to engage each other with an easy and gradual contacting effect thereby preventing accidental breakage of the window panes when the inner sash is pushed into the closed position.

HERMAN P. PORTER.
